BLOWOUT PREVENTER

Elmo O. Lowe, Los Angeles, Calif.

Application February 5, 1940, Serial No. 317,229

16 Claims. (Cl. 137—139)

This invention relates to a device for use on oil and gas wells and relates more particularly to a control head or blowout preventer. A general object of this invention is to provide a simple, practical, blowout preventer that is positive and dependable in operation.

In drilling deep wells such as oil wells and gas wells, very high pressures are sometimes encountered in the earth formations penetrated by the well. This pressure often develops very rapidly and sometimes blows out around the drilling tools, causing considerable damage. Control devices known as blowout preventers are provided at the upper ends of the well casings to control the high pressures that may suddenly develop during drilling operations. Ram type blowout preventers have gone into extensive use but considerable difficulty is encountered in providing effective fluid-tight seals between the surfaces of the rams and the bodies of the devices. It has been the general practice to employ packing of rubber, or the like, to seal between the rams and the bodies. This rubber packing is not dependable and soon wears or cuts out, necessitating difficult, time consuming repacking operations.

Another object of this invention is to provide an effective blowout preventer in which dependable, fluid-tight seals are provided at the upper and lower surfaces of the rams without resorting to the use of rubber packing, or the like.

Another object of this invention is to provide a blowout preventer of the ram type, embodying novel means for providing effective, dependable seals at both the upper and lower sides of the rams.

Another object of this invention is to provide a blowout preventer in which the rams are tightly brought against seats on the upper and lower walls of the body when they reach their sealing positions about the pipe to provide seals at the upper and lower sides of the rams.

Another object of the invention is to provide a blowout preventer of the character mentioned embodying novel expansible packing means on the rams inflated by fluid pressure to assure fluid-tight seals about the pipe or object.

Another object of this invention is to provide a blowout preventer of the character mentioned that is simple and inexpensive to manufacture and that is compact and light in weight.

The various objects and features of my invention will be fully understood from the following detailed description of a typical preferred form and application of the invention, throughout

which description reference is made to the accompanying drawings, in which:

Fig. 1 is a side elevation of the blowout preventer of this invention. Fig. 2 is a top or plan view taken as indicated by line 2—2 on Fig. 1 with certain parts in horizontal cross section. Fig. 3 is an enlarged, fragmentary vertical detailed sectional view of the device showing the rams in the closed positions with the drill pipe removed. Fig. 4 is a horizontal detailed sectional view taken as indicated by line 4—4 on Fig. 3 showing the rams in open positions with the drill pipe removed. Fig. 5 is a fragmentary vertical detailed sectional view taken as indicated by line 5—5 on Fig. 3. Fig. 6 is an enlarged fragmentary vertical detailed sectional view taken as indicated by line 6—6 on Fig. 4. Fig. 7 is a fragmentary vertical detailed sectional view taken as indicated by line 7—7 on Fig. 6, and Fig. 8 is an enlarged sectional view of one of the packing parts.

The blowout preventer of this invention may be said to comprise, generally, a body 10 to be connected with the well casing or other well equipment, a pair of closure gates or rams 11 operable in the body 10, means 12 for moving the rams 11 between their open and closed positions, and means 13 for moving the rams laterally to seal with the interior of the body 10 when the rams reach the closed positions.

The body 10 is a hollow structure adapted to be connected with the upper end of the well casing and serves to contain the closures or rams 11. The body 10 may be varied considerably in design and construction without departing from the invention. In the construction illustrated the body 10 has a central depending part 14 provided at its lower end with a flange 15 for connection with the casing C, a head, or a valve on the casing. An internally threaded part 16 projects from the upper end of the body 10 to receive a casing section S. A central vertical opening 17 extends through the body 10 and its projecting parts 14 and 16, and communicates with the well casing. The major portion of the body 10 has a transverse chamber or opening 18 intersecting the vertical opening 17.

An access window or opening 19 is provided in a side wall of the body 10 to communicate with the opening 18. The access opening 19 is closed by a cover or plate 20. The plate 20 may be removably secured to the body 10 by screws or bolts 21. The inner side of the plate 20 is complementary to the opposing wall of the body 10. The inner side of the plate 20 and the said op-

posing wall of the body 10 have horizontal guideways 21 provided with flat upper and lower walls. Raised annular seats 22 are provided on the upper and lower walls of the opening 18 in surrounding relation to the vertical opening 17. As best illustrated in Fig. 5 of the drawings the seats 22 are finished and flat and are pitched to be in converging relation. The surfaces of the seats 22 are pitched laterally and in the case illustrated converge toward the closed wall of the body 10 having the guide way 21.

The closure gates or rams 11 operate in the opening 18 between the open positions illustrated in Fig. 4 where they are clear of the opening 17 and the closed position illustrated in Figs. 2, 3 and 5 where they may engage about a drill pipe P or other object extending into the well. The rams 11 are alike and are arranged in the opening 18 in opposing relation. In the case illustrated where the rams 11 are intended to seal about the pipe P the rams are semi-annular, having opposed vertical notches 23 in their inner sides for receiving or cooperating with the pipe P. The rams 11 are designed to move in the opening 18 with freedom and have flat, generally horizontal upper and lower sides. In accordance with the invention the rams 11 are supported to move toward and away from one another and to move laterally relative to the direction of the first named movement. Pairs of lugs 24 project laterally from the opposite sides of the rams 11 adjacent the inner ends of the rams and have flat upper and lower faces 25 which ride on the walls of the guideways 21. The lugs 24 may have clearance with the side walls of the guideways 21 to permit free movement of the rams. Substantially central tail lugs 26 are provided on the upper and lower sides of the rams 11 to ride in grooves 27 in the upper and lower walls of the opening 18. The lugs 26 may project from the rear sides of the rams 11, as best illustrated in Fig. 4 of the drawings and are free to move laterally in the grooves 27. The engagement of the lugs 26 in the grooves 27 stabilizes the rams 11 and prevents tipping of the rams.

The upper and lower sides of the rams 11 are formed to seal with the body seats 22 to prevent the leakage of fluid under pressure around the rams. Substantially semi-circular raised sealing ridges 28 are provided on the upper and lower sides of the rams 11. The ridges 28 are preferably at the peripheries of the rams. It is preferred to form the ridges 28 of a material different from that of the body 10 and in practice the ridges may be formed of bronze, or the like. The surfaces of the sealing ridges 28 are formed and finished to evenly bear against and seal with the converging surfaces of the body seats 22. As best illustrated in Fig. 5 of the drawings the sealing ridges 28 are pitched or convergent so that the rams 11 may be said to be wedge-shaped in edge or face elevation. The sealing ridges 28 converge in the same direction as the body seats 22 and their surfaces are at substantially the same angle as the surfaces of the seats to evenly and effectively seal with the seats when the rams are moved laterally. If desired, the upper and lower sides of the rams 11 may be provided with packing instead of or in addition to the ridges 28.

The faces or inner sides of the rams 11 are preferably provided with packing to seal one with the other and to pack about the pipe P. In the form of the invention illustrated there are two spaced sealing members 30 provided on the inner side of each ram 11. The sealing members 30 may be formed of rubber, synthetic rubber, or

the like, to be compressible and resilient. Dovetailed grooves 31 are formed in the inner faces of the rams 11 and in the walls of the notches 23 to receive the packing members 30. The members 30 are spaced one above the other and extend from adjacent the opposite sides of the rams. As illustrated in Fig. 5 of the drawings the packing members 30 have vertical branches 32 extending to the upper and lower sides of the rams 11. When the rams 11 are in their closed positions the packing members of one ram tightly seal against the packing members of the other ram and the portions of the packing members in the notches 23 tightly pack about the pipe P. The packing members 30 may be solid or may be inflatable as illustrated. The means for inflating the packing members 30 will be hereinafter described. The inflatable members 30 illustrated have continuous grooves 30a in their inner sides and longitudinal cavities or chambers 30b in their outer parts connected with the grooves 30a by ports 30c.

The means 12 for operating or moving the rams 11 is operable to simultaneously move the two rams 11 between the open and closed positions. The means 12 is a screw means including two spaced horizontal screws 33. The screws 33 extend longitudinally through the guideways 21 with clearance and the opposite ends of the screws are rotatably supported. One screw 33 has an end portion rotatably received in an opening 34 in the body wall and the other screw 33 has its inner end received in a similar opening 35 in the plate 20. Plugs 36 are removably threaded in the openings 34 and 35 and are socketed to rotatably receive the end portions of the screws 33. The other ends of the screws 33 are releasably coupled with stems 37. Bosses 38 and 39 are provided on the body 10 and the plate 20 respectively and have openings 40 and 41 rotatably receiving the stems 37. The stems 37 are provided with polygonal sockets 42 that receive correspondingly shaped end parts 43 of the screws 33 so that the screws turn with the stems 37. The stems 37 extend outwardly through suitable packing glands 44 on the bosses 38 and 39 to project at the exterior of the device.

Collars 9 are fixed to the stems 37 to engage the adjacent ends of guideways 21 to hold the stems against displacement and endwise movement.

The screws 12 may be rotated or operated by an available or selected power means. In the construction illustrated sprockets 45 are fixed to the projecting parts of the stems 37 and a chain 46 operates over the sprockets so that the screws 33 may be simultaneously rotated. A second sprocket 47 is fixed to one of the stems 37 and a drive chain 48 operates over the sprocket 47. The drive chain 48 may extend to a remote drive means or power means for operating the blow-out preventer.

Each screw 33 has a right-hand thread 49 and a lefthand thread 50 and internally threaded nuts 51 cooperate with the threads 49 and 50. The nuts 51 are shaped and proportioned to be received between the lugs 24 on the sides of the rams 11. The nuts 51 may be received in the guideways 21 with suitable clearance. It will be seen that rotation of the screws 33 causes cooperation between the threads of the screws 33 and the threads of the nuts 51 so that the nuts react against the lugs 24 to move the rams 11 toward or away from one another.

The means 13 for moving the rams 11 laterally

to seal with the body seats 22 are important features of the invention. The means 13 operate automatically when the rams 11 have been forced together in their closed positions and move the closed rams laterally so that their sealing ridges 28 wedge between and seal with the body seats 22. The means 13 include toothed racks 52 on the opposite sides of the rams 11. In practice the racks 52 may be in the nature of webs connecting or joining the lower portions of the adjacent lugs 24. The upper sides of the racks 52 carry series of gear teeth 53.

The means 13 further include series of gear teeth 54 on the peripheries of the traveling nuts 51 engaging the adjacent rack teeth 53. The teeth 54 of the nuts 51 mesh with the rack teeth 53 at all times. Continued rotation of the screws 33 following the full closing of the rams 11 results in turning of the nuts 51 and the teeth 54 meshing with the teeth 53 shift the rams 11 laterally so that the sealing ridges 28 are wedged against the body seats 22 to provide seals at the upper and lower sides of the rams. The side wall of the guideway 21 in the body 10 is notched or relieved at 59 to receive the adjacent lugs 24 when the rams 11 are moved laterally. As best illustrated in Fig. 4 of the drawings the rams 11 are initially eccentric with respect to the vertical opening 17, that is, the common horizontal center line of the rams 11 is offset from the vertical axis of the opening 17. During the above described lateral movement of the rams 11 the rams move toward positions where their notches 23 are concentric with the vertical axis of the opening 17. The eccentricity of the rams 11 and the pitch or inclination of the body seats 22 and the sealing ridges 28 are exaggerated in the drawings to better illustrate the invention.

The invention preferably includes means for lubricating the sealing surfaces of the rams 11 and the body 10. The sealing ridges 28 of the rams 11 are provided with arcuate lubricant grooves 55. The grooves 55 preferably extend throughout the major portions of the ridges 28. Lubricant ports 56 extend vertically through the walls of the body and extend into the body parts 14 and 16. The inner ends of the ports 56 are located so that they communicate with the grooves 55 when the rams 11 are in the closed positions. Tubes or pipes 57 communicate with the outer ends of the ports 56 and extend to a common manifold 58, see Fig. 2. The manifold 58 may extend to a remote source of lubricant under pressure or to a remote means for placing the lubricant in the system under a high pressure. The lubricant supplied to the grooves 55 effectively lubricates the sealing surfaces of the bearing ridges 28 and the surfaces of the body seats 22 and aids in providing fluid tight seals.

Where the above described inflatable packing members 30 are employed the lubricating means may be employed to expand or inflate the members. As illustrated in Fig. 4 the ends of the lubricant grooves 55 join the ends of the grooves 30^a. Lubricant under pressure supplied to the grooves 55 as above described passes into the grooves 30^a and chambers 30^b to actuate or expand the packing members. The lubricant under pressure in the grooves 30^a expands the members 30 in the dovetailed grooves 31, dependably retaining the members in the grooves. The lubricant under pressure in the chambers 30^b expands the members 30 to have tight sealing engagement with one another and with the pipe P to

positively prevent the leakage of well fluid and pressure.

During the normal drilling operations the rams 11 are in their open or retracted positions where they do not interfere with the free passage of tools and equipment through the opening 17. When high fluid pressures suddenly develop in the well the chain 48 is driven or operated by a convenient or available power means to rotate the screws 33. Rotation of the screws 33 causes movement of the rams 11 toward their closed positions. The rams 11 move together until their sealing members 30 cooperate at the faces of the rams and until the sealing members engage about the pipe P or other object extending into the well. In practice the rotation of the screws 33 causes the nuts 51 to travel along the screws to bring the sealing members 30 into tight cooperation and into tight engagement with the pipe P. This tight cooperation of the rams 11 and the engagement of the rams with the pipe P stops the inward movement of the rams. Continued rotation of the screws 33 when the inward movement of the rams is stopped results in turning of the nuts 51, the nuts being unable to continue their travel along the screws. Upon turning of the nuts 51, the teeth 54 meshing with the teeth 53 shift the rams 11 laterally or toward the notch 59. This shifting of the rams may be slight. However, it is sufficient to bring the faces of the sealing ridges 28 into tight sealing engagement with the surfaces of the body seats 22. Sufficient power may be applied in turning the screws 33 to assure the even and tight sealing engagement of the sealing ridges 28 with the body seats 22. This engagement of the ridges 28 with the seats 22 provides complete annular seals between the rams and the body 10 above and below the rams to positively prevent the leakage of fluid around the rams.

When the well has been killed or the pressure condition relieved, the screws 33 are rotated in a reverse direction to retract the rams 11. At the start of this reverse rotation of the screws 33 the wedging engagement of the ridges 28 with the seats 22 resists movement of the nuts 51 along the screws 33 and the nuts turn so that the teeth 54 cooperate with the teeth 53 to move the rams laterally toward their initial eccentric positions, thus freeing the sealing ridges 28 from the body seats 22. Continued reverse rotation of the screws 33 causes the nuts 51 to travel along the screws 50 and the nuts move the rams 11 back to their retracted positions.

When it becomes desirable or necessary to clean out the body 10 the plugs 36 may be removed and steam or water discharged into the body through the openings 35. If it is desired to replace, repack or service the rams 11, the plate 20 is removed and moved laterally from the body 10 to disengage the nuts 51 from the adjacent sides 60 of the rams 11. The rams 11 may then be moved out through the opening 19. The rams 11 may be easily and quickly removed and replaced. The improved blowout preventer of the present invention is small and compact and is light in weight and may be easily mounted in any selected position, for example, it may be mounted in the cellar of the derrick, at the derrick floor, or above the derrick floor, as desired.

Having described only a typical preferred form and application of my invention, I do not wish to be limited or restricted to the specific details herein set forth, but wish to reserve to myself any variations or modifications that may appear to those skilled in the art or fall within the scope of the following claims.

I claim:

1. A blowout preventer for controlling a well comprising a body having an opening for communicating with the well, spaced converging seats in the body, closure members movable in the body between retracted positions and active positions where they engage one another in the opening between the seats, means for moving the closure members from the retracted positions to the active positions in engagement with one another, and means made operative by said engagement of the members with one another for moving the closure members laterally when they reach the active positions to wedge the members between the converging seats.

2. A blowout preventer for controlling a well comprising a body having a substantially vertical opening for communicating with the well, vertically spaced sealing seats in the body around the opening, two closure members movable toward one another in the body in a substantially horizontal line between retracted positions and active positions in the opening where they engage one against the other between the seats, means for moving the closure members to said active positions, convergent sealing faces on the upper and lower sides of the members, and means for moving the members horizontally in a direction lateral with respect to said line after they have reached said active positions to bring said sealing faces against the seats.

3. A blowout preventer for controlling a well comprising a body having a substantially vertical opening for communicating with the well, vertically spaced seats in the body at the opening, closure members in the body movable between retracted positions and active positions between said seats where they engage one against the other, said seats converging in a generally horizontal direction lateral of the direction of said movement of the members, convergent sealing surfaces on opposite sides of the members, and means made operative by the engagement of the members one with the other for moving the members laterally to bring said surfaces into sealing cooperation with the seats.

4. A blowout preventer for controlling a well comprising a body having a substantially vertical opening for communicating with the well, seats on the upper and lower walls of the body around the opening, closure members in the body movable toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a generally horizontal direction transverse of said movement of the closure members, and means conditioned by said engagement of the members with one another for moving the members in a generally horizontal direction transverse of said movement to bring said surfaces into wedging and sealing cooperation with the seats.

5. A blowout preventer for controlling a well comprising a body having a substantially vertical opening for communicating with the well, seats on the upper and lower walls of the body around the opening, closure members in the body movable along a substantially horizontal line toward one another from inactive positions to active positions in engagement with one another.

between the seats, sealing means on the members cooperating when the members are in said active positions, means for moving the members to said active positions, sealing surfaces on the upper and lower sides of the members, said seats and surfaces being correspondingly convergent in a generally horizontal direction transverse of said horizontal line of movement of the closure members, and gear means automatically made operative by said engagement of the members when the members reach their active positions to move the members in a generally horizontal direction transverse of said line of movement so that the surfaces seal with the seats.

6. A blowout preventer for controlling a well comprising a body having a substantially vertical opening for communicating with the well, seats on the upper and lower walls of the body around the opening, closure members in the body movable along a substantially horizontal line toward one another from inactive positions to active positions in engagement with one another between the seats, sealing means on the members cooperating when the members are in said active positions, screw means for simultaneously moving the members to their active positions, sealing surfaces on the upper and lower sides of the members, said seats and surfaces converging in a generally horizontal direction transverse of said line of movement of the members, and means operated by the screw means and made operative by the engagement of the members upon reaching their active positions for moving the members in a generally horizontal direction transverse of said line of movement to bring said surfaces into sealing cooperation with the seats.

7. A blowout preventer for controlling a well comprising a body having an opening for communicating with the well, seats on the upper and lower walls of the body around the opening, closure members in the body movable along a generally horizontal line toward one another from inactive positions to active positions in engagement with one another between the seats, sealing means on the members cooperating when the members are in said active positions, means for moving the members to said active positions including rotatable screws and turnable traveling nuts on the screws engaging the members, sealing surfaces on the upper and lower sides of the members, the seats and sealing surfaces being convergent in a generally horizontal direction transverse of said line of movement of the members, and means idle during said movement of the members and made operative by said engagement of the members with one another for moving the members in a generally horizontal direction transverse of said line of movement from their active positions to wedge said surfaces against the seats to seal with the same.

8. A blowout preventer for controlling a well comprising a body having an opening for communicating with the well, seats on the upper and lower walls of the body around the opening, closure members in the body movable along a generally horizontal axis toward one another from inactive positions to active positions in engagement with one another between the seats, sealing means on the members cooperating when the members are in said active positions, means for moving the members to said active positions including rotatable screws and turnable traveling nuts on the screws engaging the members, sealing surfaces on the upper and lower sides of the members, the seats and sealing surfaces being convergent in a generally horizontal direction

transverse of said axis of movement of the members, and means for moving the members in a generally horizontal direction transverse of said line of movement from their active positions to wedge said surfaces against the seats to seal with the same, the last named means including meshing gear teeth on the closure members and nuts.

9. A blowout preventer for controlling a well comprising a body having an opening for communicating with the well, seats on the upper and lower walls of the body around the opening, closure members in the body movable toward one another from inactive positions to active positions in engagement with one another between the seats, sealing means on the members cooperating when the members are in said active positions, means for moving the members to said active positions including rotatable screws and turnable traveling nuts on the screws engaging the members, sealing surfaces on the upper and lower sides of the members, the seats and sealing surfaces being convergent in a direction transverse of said movement of the members, and means for moving the members transversely from their active positions to wedge said surfaces against the seats to seal with the same, the last named means comprising transverse toothed racks on the members and series of teeth on the nuts cooperating with the racks to move the members transversely.

10. A blowout preventer for controlling a well comprising a body having an opening for communicating with the well, seats on the upper and lower walls of the body around the opening, closure members in the body movable along a generally horizontal axis toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a generally horizontal direction transverse of said axis of movement of the closure members, means made operative by the cooperation of the members in their active positions for moving the members substantially horizontally in a direction transverse of said axis of movement to bring said sealing surfaces into sealing cooperation with the seats, and means for lubricating the sealing surfaces.

11. A blowout preventer for controlling a well comprising a body having an opening for communicating with the well, seats on the upper and lower walls of the body around the opening, closure members in the body movable along a generally horizontal axis toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a generally horizontal direction transverse of said axis of movement of the closure members, means made operative by said engagement of the members with one another for moving the members in a generally horizontal direction transverse of said axis of movement when the members are in cooperation in their active positions to bring said sealing surfaces into sealing cooperation with the seats, and

means for supplying lubricant under pressure to the cooperating seats and surfaces.

12. A blow out preventer for controlling a well comprising a body having an opening for communicating with the well, seats on the upper and lower walls of the body around the opening, closure members in the body movable along a generally horizontal axis toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a generally horizontal direction transverse of said movement of the closure members, said seats and surfaces being metallic, and means made operative by the engagement of the members with one another for moving the members horizontally in a direction transverse of said axis of movement when the members reach their active positions to bring said surfaces into wedging and sealing cooperation with the seats.

13. A blowout preventer for controlling a well comprising a body having an opening for communicating with the well, seats on the upper and lower walls of the body around the opening, closure members in the body movable toward one another from inactive positions to active positions in engagement with one another between the seats, sealing means on the members cooperating when the members are in said active positions, means for moving the members to said active positions including rotatable screws at opposite sides of the pair of members, lugs on the sides of the members, traveling nuts on the screws cooperating with the lugs to move the members upon rotation of the screws, and means for simultaneously rotating the screws, and means for shifting the members laterally when in their active positions to bring said surfaces into sealing cooperation with the seats including transverse series of gear teeth on the members, and gear teeth on the nuts meshing with the teeth on the members to shift the members transversely when the nuts turn.

14. A blowout preventer for controlling a well comprising a body having an opening for communicating with the well, seats on the upper and lower walls of the body around the opening, closure members in the body movable along a generally horizontal axis toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a horizontal direction transverse of said axis of movement of the closure members, means idle during the movement of the members toward one another and made operative by the engagement of the members with one another for moving the members horizontally in a direction transverse of said axis when the members are in cooperation in their active positions to bring said sealing surfaces into sealing cooperation with the seats, inflatable packing on the inner sides of the members, and means for conducting fluid under pressure to the packing to inflate the same.

15. A blowout preventer for controlling a well

comprising a body having an opening for communicating with the well, seats on the upper and lower walls of the body around the opening, closure members in the body movable toward one another from inactive positions to active positions in engagement with one another between the seats, sealing means on the members cooperating when the members are in said active positions, means for moving the members to said active positions, sealing surfaces on the upper and lower sides of the members, said seats and surfaces being correspondingly convergent in a direction transverse of said movement of the closure members, means for moving the members transversely when they are in cooperation in their active positions to bring said sealing surfaces into sealing cooperation with the seats, said sealing surfaces having grooves, expandible inflatable packing parts on the inner sides of the members having

their interiors in communication with the grooves, and means for supplying lubricant under pressure to the grooves to lubricate the seats and said surfaces and to inflate the packing parts.

16. A blowout preventer for application to a well casing comprising a body having an opening for communicating with the casing, rams in the body movable in a substantially horizontal line from retracted positions to active positions where they seal one against the other and extend across said opening to close the same, means for moving the rams along said line toward one another to said active positions, and means idle during said movement of the rams for moving the rams in a direction substantially normal to said line to seal with the body after they have reached their active positions.

ELMO O. LOWE.
